US00D472438S

(12) **United States Design Patent** (10) Patent No.: **US D472,438 S**
 Peperkorn et al. (45) Date of Patent: ** Apr. 1, 2003

(54) **LOCKING PLIERS WITH TOOLSET POCKET**

(75) Inventors: **William D. Peperkorn**, DeWitt, NE (US); **Brian L. Rahe**, DeWitt, NE (US); **Thomas O. Miller**, DeWitt, NE (US)

(73) Assignee: **American Tool Companies, Inc.**, Hoffman Estates, IL (US)

(**) Term: **14 Years**

(21) Appl. No.: **29/152,268**

(22) Filed: **Oct. 29, 2001**

(51) LOC (7) Cl. **08-05**

(52) U.S. Cl. **D8/52**

(57) **CLAIM**

The ornamental design for locking pliers with toolset pocket, as shown and described.

DESCRIPTION

FIG. 1 is a perspective view of an embodiment of the locking pliers with toolset pocket;

FIG. 2 is a top view of the embodiment of FIG. 1;

FIG. 3 is a bottom view of the embodiment of FIG. 1;

FIG. 4 is a side view of the embodiment of FIG. 1;

FIG. 5 is a side view of the embodiment of FIG. 1;

FIG. 6 is a rear view of the embodiment of FIG. 1; and,

FIG. 7 is a front view of the embodiment of FIG. 1.

The dotted lines indicate components for illustrative purposes only and form no part of the subject design.
